UNITED STATES PATENT OFFICE.

JOSEPH L. SMITH, OF BUFFALO, NEW YORK, ASSIGNOR OF ONE-HALF TO HERBERT B. SMITH, OF BUFFALO, NEW YORK.

DESIGN FOR A SMOKER'S STAND.

Application filed October 8, 1925. Serial No. 15,067. Term of patent 14 years.

To all whom it may concern:

Be it known that I, JOSEPH L. SMITH, a citizen of the United States, residing at Buffalo, in the county of Erie and State of New York, have invented a new, original, and ornamental Design for Smoker's Stand, of which the following is a specification, reference being made to the accompanying drawing, forming part thereof.

Fig. 1 shows a side elevation of a smoker's stand, showing my new design.

Fig. 2 is a plan view thereof.

What I claim is:

The ornamental design for a smoker's stand as shown.

JOSEPH L. SMITH.
